DESIGN FOR A FUNERAL URN OR SIMILAR
ARTICLE

Thomas H. Jones, Washington, D. C., assignor to
the United States of America as represented by
the Secretary of War

Application March 12, 1947, Serial No. 137,563

Term of patent 14 years

(Cl. D19—1)

To all whom it may concern:

Be it known that I, Thomas H. Jones, a citizen of the United States and resident of the city of Washington, in the District of Columbia, have invented a new, original, and ornamental Design for a Funeral Urn or Similar Article, of which the following is a specification, reference being had to the accompanying drawing, forming a part thereof.

Fig. 1 is an elevational view of a funeral urn, showing my new design.

Fig. 2 is another elevational view of the same, taken from a position diametrically opposite that of Fig. 1.

Fig. 3 is a plan view of the same.

The essential features of my design reside in the portions shown in full lines.

I claim:

The ornamental design for a funeral urn or similar article, as shown and described.

THOMAS H. JONES.
